Primary Examiner — Christian P. McLean*(74) Attorney, Agent, or Firm* — Ying-Ting Chen(57) **CLAIM**

The ornamental design for a strength trainer as shown and described.

DESCRIPTION

FIG. 1 is a perspective view of strength trainer showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a perspective view showing my new design arranged with a pairs of grip units.

The broken lines are directed to portions of the strength trainer that form no part of the claimed design. The additional broken lines in FIG. 9 are directed to environment and are for illustrative purposes only; the broken lines form no part of the claimed design.

1 Claim, 9 Drawing Sheets(56)
